UNITED STATES PATENT OFFICE.

SEYBERT J. SMITH, OF CHADWICK, ILLINOIS.

COUNTER GUARD.

Application filed January 28, 1925. Serial No. 5,404.

To all whom it may concern:

Be it known that I, SEYBERT J. SMITH, citizen of the United States, residing at Chadwick, in the county of Carroll and 5 State of Illinois, have invented certain new and useful Improvements in a Counter Guard, of which the following is a specification.

This invention relates to improvements in 10 counter guards, and is more particularly adapted to a protector for use in commercial institutions such as banks for protecting the cashier against an attempted hold-up by burglars.

15 One of the important objects of the present invention is to provide a counter guard wherein the protector which shields the cashier when an attempt is made to hold him up, may be actuated either by the cashier or by 20 other persons in other parts of the room or building.

A still further object of the invention is to provide a counter guard of the above mentioned character, wherein the guard 25 normally provides a desk lid, the latch which normally holds the guard in the position for use as a desk lid, being adapted to be released by a suitable foot control mechanism, means being associated with the guard for 30 automatically swinging the same upwardly into inoperative position as a protector shield for the cashier when latch is released.

A still further object is to provide a 35 counter guard of the above mentioned character, which is simple in construction, inexpensive, and furthermore adapted for the purposes for which the same is designated.

Other objects and advantages of this 40 invention will become apparent during the course of the following description.

In the accompanying drawing forming 45 part of this specification and which like numerals designate like parts throughout the same:

Figure 1 is a sectional view through the counter and window of a cashier's cage showing the manner in which the lid is associated with the counter, the actuating means for 50 the lid being shown in elevation, and

Fig. 2 is a detail of the spring hinge which secures the lid to the inner edge of the counter.

In the drawing wherein for the purpose 55 of illustration is shown the preferred embodiment of my invention, the numeral 1

designates the counter of a cashier's cage, the cashier's window arranged above the counter being illustrated generally at 2. A lid 3 is secured to the inner edge of the counter 1 at a point adjacent the window 2 by suitable spring hinges such as is shown generally at 4. The upper face of the lid has secured thereto the bullet-proof shield or plate 5. When used as a desk, the lid 3 60 is inclined downwardly toward its outer free edge as clearly illustrated in Fig. 1.

A bracket 6 is secured below the counter 1 adjacent the inner edge thereof. A curved arm 7 is secured at one end to the underside of the lid 3 at a point adjacent the hinged end thereof, the free end of said curved arm extending through a suitable opening provided therefor in the bracket 6. 70

The free end of the curved arm which is 75 in the form of a rod is threaded and receives a nut 8 whereby the displacement of the free end of the curved arm from the opening in the bracket is prevented, when the lid 3 is swung in a manner to be hereinafter more 80 fully described.

An expensible coiled spring 9 encircles 85 the curved arm 7 and is disposed between the underside of the hinged lid 3 and the bracket 6.

A tongue 10 is secured to the bottom face of the hinged lid 3 and cooperating therewith is the pivoted latch 11, the same being supported in the outer end of a supporting arm 12, the inner end of which is secured to the bracket 6. When the latch 11 is in engagement with the tongue 10, the hinged lid 3 is in the position as shown in Fig. 1 and the expansible coiled spring 9 is placed under tension as is also the spring 95 13 associated with each of the hinges 4. The latch and tongue cooperate to permit the lid to be used as a desk by the cashier behind the counter.

For the purpose of releasing the latch 100 from engagement with the tongue 10, there is provided a chain 14, the upper end being secured to the pivoted latch, the lower end extends through a suitable opening 15 provided in the floor 16. A foot treadle 17 is 105 pivotally supported as at 18 in a suitable bracket secured on the floor and the same is operatively connected to the adjacent portion of the chain 14. The provision of the foot treadle 17 enables the cashier to control or actuate the releasing of the latch for 110 the tongue whenever it becomes necessary.

In order that the latch may be released from a point remote from the cashier's cage by other persons in various parts of the building upon being given a sufficient warning, provide a chain 19, the same being secured to the lower end of the chain 14 and extending over suitable guide pulleys 20 and being secured at its opposite end to a foot treadle 21 which is disposed or supported on the floor below the first mentioned floor. An additional chain 22 is also secured to the lower end of the chain 14 and is trained over suitable guide pulleys 23 similar to the guide pulley 20, the chain 22 being secured at its opposite ends to a foot treadle 24 located on the upper floor.

It is to be understood that any number of additional chains may be operatively connected to the main chain 14 whereby the latch mechanism may be actuated from any suitable point remote from the cashier's cage.

From the foregoing description, it will be seen that when a burglar attempts to hold up the cashier, by actuating the chain 14, the latch 11 will be released from engagement with the tongue 10 and the coiled spring 9 as well as the spring 13 associated with the hinges will automatically swing the lid 3 upwardly to the position shown in the dotted line, thereby shielding the cashier against being shot by the bullet fired by the burglar through the window 2. The metallic plate 5 which is constructed of bullet-proof material will deflect the bullets striking the lid, thus protecting the cashier against serious injury.

While I have shown the preferred embodiment of my invention, it is to be understood that various changes in the size, shape, and arrangement of parts may be resorted to without departing from the spirit of the invention and the scope of the appended claims.

Having thus described my invention, what I claim as new is:—

In combination with a counter, and a cashier's window above the same, an upwardly swinging lid hingedly secured to the inner edge of said counter adjacent said window, a bracket supported below the counter, a supporting arm secured at one end to said bracket and extending inwardly below said lid, a tongue secured on the bottom of the lid, a pivoted latch supported on the inner edge of said supporting arm and engaging said tongue for normally holding the lid in a position for use as a desk, foot operated means for releasing said latch from engagement, means for automatically swinging the lid upwardly to provide a protector shield for a person behind the window, said last mentioned means comprising a curved arm secured at one end to the bottom of the lid, the free end of said curved arm being disposed through an opening provided therefor in said supporting bracket, and an expansible coiled spring encircling the curved arm and disposed between said bracket and the bottom of the lid.

In testimony whereof I affix my signature.

SEYBERT J. SMITH.
